DESIGN FOR A COMBINATION HANDBAG

Ida Jolles, New York, N. Y.

Application August 20, 1940, Serial No. 94,529

Term of patent 3½ years

To all whom it may concern:

Be it known that I, Ida Jolles, a citizen of the United States of America, residing in New York city, in the Borough of Manhattan, county and State of New York, have invented a new, original, and ornamental Design for a Combination Handbag, of which the following is a specification, reference being had to the accompanying drawing, forming part thereof, wherein:

Figure 1 is a front elevational view of a combination handbag showing my new design, in the position when used as a short handbag.

Figure 2 is a rear elevational view thereof.

Figure 3 is a front elevational view of the combination handbag shown in Figure 1, used as a long handbag, and showing the supplemental opening at the bottom.

Figure 4 is a side elevational view of the combination handbag shown in Figure 3, on a smaller scale.

I claim:

The ornamental design for a combination handbag, substantially as shown.

IDA JOLLES.
